UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

STITCH-FORMING MECHANISM FOR SEWING-MACHINES.

1,350,326.

Specification of Letters Patent. Patented Aug. 24, 1920.

Application filed June 16, 1915. Serial No. 34,426.

To all whom it may concern:

Be it known that I, JAMES R. MOFFATT, a citizen of the United States, residing at Chicago, in the county of Cook, State of Illinois, have invented certain new and useful Improvements in Stitch-Forming Mechanism for Sewing-Machines, of which the following is a description, reference being had to the accompanying drawing and to the figures of reference marked thereon.

The invention relates to new and useful improvements in stitch forming mechanism for sewing machines, and more particularly to a cross thread laying mechanism coöperating with the needles above the work support.

An object of the invention is to provide a cross thread laying mechanism having a thread guiding eye movable in a direction parallel to the line of feed and a thread hook operating in front of the needles and in a path at right angles to the line of feed, with means for operating both of said elements from a vertical shaft mounted in the supporting head for the presser bar and needle bar.

A further object of the invention is to provide a construction of the above character, wherein the vertical shaft also serves the purpose of an auxiliary presser bar to prevent the main presser bar from oscillating in its bearings.

These and other objects will in part be obvious and will in part be hereinafter more fully disclosed.

In the drawings which show by way of illustration one embodiment of the invention,—

Figure 1 is a rear view of a sewing machine having my improvements applied thereto;

Fig. 2 is an end elevation, certain of the parts being omitted to avoid confusion;

Fig. 3 is a view partly in end elevation and partly in section, showing a part of the supporting head of the overhanging arm, the feed, one of the needles, the looper, the work support and the relation of my improved thread laying mechanism thereto;

Fig. 4 is a view partly in section and partly in plan, showing the work support, the feed, presser foot and the thread laying mechanism which coöperates with the needles;

Fig. 5 is a detail showing the supporting bracket for the bar which supports the thread guide;

Fig. 6 is a detail showing in plan the immediate mechanism for actuating the thread hook;

Fig. 7 is a view partly in section showing one of the arms for preventing the presser bar from turning and its relation to the operating shaft for the cross thread laying mechanism;

Fig. 8 is a detail showing diagrammatically the cross threads and the manner of holding the same for the needles;

Fig. 9 is a detail showing one position of the controlling eyes for the cross thread; and

Fig. 10 is a similar view showing another position of the movable thread eye.

The sewing machine to which my invention is applied consists of a supporting bed 1, carrying a standard 2, on which is mounted an overhanging arm 3. Said overhanging arm has a supporting head 4 at its forward end, in which the needle bar 5 reciprocates. Said needle bar 5 carries the needles 6 and 7. Said needle bar is reciprocated in the usual way from a needle lever mounted in the overhanging arm.

The bed plate is also provided with a work support 8 beneath which operates the feed dog 9. This feed dog is of the usual character and further description thereof is not thought necessary. Coöperating with the feed dog is a presser foot 10 which is carried by a presser bar 11. The presser bar 11 is mounted in the supporting head 4 and may be raised by a hand lever 12 or a foot controlled lever 13.

Coöperating with the needle is a cross thread laying mechanism consisting of a reciprocating thread guide 14 and a loop forming hook 15. The thread guide 14 is fixed to a bar 16 which is mounted so as to reciprocate in bearings 17-17 in a bracket 18, which is clamped to the presser bar 11. The hub of the bracket has projecting ears 19 through which a clamping bolt 20 extends for causing the hub to grip the presser bar. The supporting bar 16 for the thread guide 14 reciprocates in the bearings 17 and its direction of reciprocation is substantially parallel with the line of feed. Said bar 16 carries a collar 21 on its forward end and

this collar has a socket for the shank 22 of the thread guide 14, said shank being fixed in said socket by a suitable screw. The collar 21 also has a thread guiding eye 23 which projects upwardly therefrom and this thread guiding eye coöperates with the thread guiding eyes 24 and 25 which are carried by the supporting head 4 of the machine.

- 10 A collar 26 is fixed to the bar 16 and this collar is connected by a link 27 to a rocking frame 28. The rocking frame 28 has a hub which freely engages the presser bar 11. Said rocking frame at the opposite side from 15 the connection of the link 27, has a projecting arm carrying a pin 29 to which is pivoted a link 30. The other end of the link 30 is pivoted to an arm 31 which is clamped to and adjacent the lower end of 20 the auxiliary presser guide bar 32. This auxiliary presser bar 32 is mounted to oscillate, so that it may be moved endwise in bearings 34 and 35. The main presser bar has a guide arm 36 fixed thereto and this 25 arm projects rearwardly and is forked at 37, so as to engage a block 38 freely journaled on the auxiliary presser bar. A collar 39 is fixed to the auxiliary presser bar, directly above said arm 36. When the main presser 30 bar 11 is raised this arm 36 lifts the auxiliary presser bar 32. Said auxiliary presser bar, however, is free to oscillate in its supporting bearings, as above described. There is a second guiding arm 40 at the upper end 35 of the auxiliary presser bar, which is somewhat similar in construction to the arm 36.

The auxiliary presser bar 32 has a laterally projecting arm carrying a ball stud 41. A link 42 coöperates with this ball stud at 40 one end and at the other end with a ball stud carried by an arm 43, which in turn is fixed to the shaft 44. The shaft 44 is mounted to oscillate in bearings 45 and 46 on the overhanging arm. Said shaft carries a fixed 45 collar 47 which is provided with an arm 48 carrying a ball stud with which an eccentric strap 49 coöperates. This eccentric strap 49 in turn coöperates with an eccentric on the main shaft 50. As the main shaft 50 rotates 50 the shaft 44 will be oscillated and this will in turn, through the link 42, oscillate the auxiliary presser bar, which becomes a vertical shaft for oscillating the rocking frame 28, and as the rocking frame 28 oscillates 55 the bar 16 will be reciprocated, so as to move the thread guide 14 back and forth in a direction parallel with the line of feed.

The thread hook 15 has a shank 51 which is mounted in an arm 52 of a rocking frame 60 53, which is freely mounted on the presser bar 11 below the rocking frame 28. This rocking frame 53 has a second arm 54, which is connected by a link 55 to an arm 56 clamped to the lower end of the auxiliary 65 presser bar 32. The oscillations of the aux-

iliary presser bar 32 will, therefore, also be imparted to the rocking frame 53 and this will move the thread hook 15 back and forth in front of the needles and in a direction substantially at right angles to the line of feed.

The needles 6 and 7 are preferably set so that a single looper 57 coöperates with both needles for joining the needle loops beneath the fabric. The thread guide 14 and the 75 thread hook 15 are each given a complete reciprocation for each complete reciprocation of the needles, so that a loop is formed in the cross thread for each reciprocation of the needles. In Fig. 8 of the drawings, 80 I have shown diagrammatically the stitches as they appear on the upper face of the fabric. Said stitches consist of the needle threads *a* and *b* and the cross thread *c*. When the needles are at the upper end of 85 their stroke the thread guide 14 is at the extreme rear end of its stroke and is just in rear of the needle 7. At this time the thread hook 15 is at the left-hand of its stroke and a loop has been formed in the cross thread *c*. 90 One strand of this loop extends in rear of both needles 6 and 7 to the previous interlocking of the cross thread with the stitches. The other strand of this loop extends from the hook between the needles to the thread guide; so that the needle 6 will enter the loop formed in the cross thread, while the needle 7 passes in front of the cross thread *c* around which the cross thread will be laid as the next loop is formed. While the needles are 100 passing beneath the material the thread hook moves forward so as to release the loop which has been formed thereby, the thread guide moves forward to a position in front of the needles and the hook again engages the cross thread for forming a new loop. As the thread guide moves forward the guiding eye 23 moves forward away from the thread guiding eyes 24 and 25, as clearly shown in 105 Fig. 10, and this will pull off thread from the supply, so that when the hook moves to form its loop, the eye 23 will give up thread thereto.

From the above description, it will be apparent that I have provided a cross thread laying mechanism, wherein both the thread guide and the thread laying hook are positively actuated from a single vertical shaft mounted in the supporting head for the needle bar and the presser bar, and, therefore, the vibrating parts are substantially short and free from lateral vibrations, so that the machine is capable of high speed stitching. It will also be obvious that I have been able to utilize the auxiliary presser bar 125 for imparting movements to the cross thread laying devices and have thereby greatly simplified the construction of the machine. It will also be noted that the thread guide and the thread hook are supported by and 130

movable with the presser bar thereby preventing interference with the presser foot, should the latter be raised at any time.

It is obvious that minor changes in the 5 details of construction and arrangement of parts may be made without departing from the spirit of the invention as set forth in the appended claims.

Having thus described my invention, 10 what I claim as new and desire to secure by Letters Patent, is:

1. The combination with a work support, a feed, a presser foot, a main presser bar, needles, and complementary stitch forming mechanism, of a cross thread laying mechanism including a thread guide movable in a direction substantially parallel with the line of feed, a thread hook coöperating therewith, an auxiliary presser bar 20 movable up and down with the main presser bar, means for oscillating said auxiliary presser bar, and devices operated by said auxiliary presser bar for actuating said thread guide and said thread hook.

2. The combination with a work support, a feed, a presser foot, a main presser bar, needles and complementary stitch forming mechanism, of a cross thread laying mechanism including a thread guide mounted to 30 move bodily back and forth in a direction parallel with the line of feed, a thread hook mounted to oscillate about the axis of the presser bar, a shaft, means for oscillating said shaft, and devices for connecting said shaft to said thread guide and said thread hook for operating the same.

3. The combination with a work support, a feed, a presser foot, a main presser bar, needles and complementary stitch forming 40 mechanism, of a cross thread laying mechanism including a thread guide, a bracket mounted on the presser bar and movable up and down therewith, a bar reciprocating in said bracket and carrying said thread guide, means for reciprocating said bar, a thread hook coöperating with said thread guide, means for pivotally supporting said thread hook on the presser bar, and means for oscillating said thread hook.

4. The combination with a work support, a feed, a presser foot, a main presser bar, needles and complementary stitch forming mechanism, of a cross thread laying mechanism including a thread guide, a bracket 55 fixed to the presser bar and having spaced arms, a rod sliding in said arms and carrying said thread guide, a horizontally oscillating rocker arm mounted on the presser bar, a link for connecting the rocker arm to said rod, and means for oscillating said rocker arm.

5. The combination with a work support, a feed, a presser foot, a main presser bar, needles and complementary stitch forming 60 mechanism, of a cross thread laying mech-

anism including a thread guide, a bracket fixed to the presser bar and having spaced arms, a rod sliding in said arms and carrying said thread guide, a rocker arm mounted on the presser bar, a link for connecting the rocker arm to said rod, an auxiliary presser bar, means for oscillating the same, an arm carried by said auxiliary presser bar, and a link for connecting said arm to the rocker arm on the main presser bar. 75

6. The combination with a work support, a feed, a presser foot, a main presser bar, needles and complementary stitch forming mechanism, of a cross thread laying mechanism including a thread guide, a bracket 80 fixed to the presser bar, and having spaced arms, a rod sliding in said spaced arms and carrying said thread guide, means for reciprocating said rod in a direction substantially parallel with the line of feed, a second thread guide carried by said rod, stationary 85 thread guides coöperating with the thread guide on said rod for pulling off and giving up cross thread to the first-named thread guide, and an oscillating thread hook coöperating with said first-named thread guide.

7. The combination with a work support, a feed, a presser foot, a main presser bar, needles, and complementary stitch forming mechanism, of a cross thread laying mechanism including a thread guide movable in 95 a direction substantially parallel with the line of feed, a thread hook coöperating therewith, an auxiliary presser bar, means for oscillating said auxiliary presser bar, 100 and devices operated by said auxiliary preser bar for actuating said thread guide and said thread hook.

8. The combination of a work support, a feed, a presser foot, a main presser bar carrying said presser foot and cross stitching mechanism including a thread guide movable in a direction substantially parallel with the line of feed, a thread hook coöperating therewith and movable in a direction substantially at right angles to the line 110 of feed, means for supporting said thread hook and said thread guide on the presser bar whereby the same are moved up and down therewith through the action of the feed on the presser foot and for removing and inserting the work, means for oscillating said thread hook and means for oscillating said thread guide.

9. The combination of a work support, a 120 presser bar, a presser foot carried thereby and cross stitch mechanism including a thread guide, a thread hook coöperating therewith, means for supporting said thread guide and thread hook on said presser bar, 125 an auxiliary presser bar and means carried by the auxiliary presser bar and movable up and down therewith for actuating the thread hook and thread guide.

10. The combination of a work support, a 130

4

presser bar, a presser foot carried thereby and cross stitch mechanism including a thread guide, a thread hook coöperating therewith, means for supporting said thread guide and thread hook on said presser bar, an auxiliary presser bar and means carried by the auxiliary presser bar and movable up and down therewith for actuating the thread hook and thread guide, and means 10 for controlling the thread of the thread guide.

11. The combination of a work support, a presser bar, a presser foot carried thereby and cross stitch mechanism including a 15 thread guide, a thread hook coöperating

therewith, means for supporting said thread guide and thread hook on said presser bar, an auxiliary presser bar and means carried by the auxiliary presser bar and movable up and down therewith for actuating the 20 thread hook and thread guide, devices carried by the supporting means for the thread guide for controlling the thread of said thread guide.

In testimony whereof I affix my signature 25 in the presence of two witnesses.

JAMES R. MOFFATT.
